UNITED STATES PATENT OFFICE.

CHARLES F. WILLARD, OF NEW YORK, N. Y., ASSIGNOR TO L-W-F. ENGINEERING COMPANY, INC., OF COLLEGE POINT, LONG ISLAND, NEW YORK, A CORPORATION OF MICHIGAN.

LANDING GEAR FOR AEROPLANES.

1,418,762.

Specification of Letters Patent. Patented June 6, 1922.

Application filed January 9, 1919. Serial No. 270,267.

To all whom it may concern:

Be it known that I, CHARLES F. WILLARD, of New York city, in the county of New York, and in the State of New York, have 5 invented a certain new and useful Improvement in Landing Gears for Aeroplanes, and do hereby declare that the following is a full, clear, and exact description thereof.

My invention relates particularly to aeroplane landing gear, and has reference to landing gear for aeroplanes of various types.

The object of my invention is to provide an advantageous supporting means for the 15 tail surfaces.

A further object is to provide a desirable form of skid construction.

Further objects of my invention will appear from the detailed description thereof 20 contained hereinafter.

While my invention is capable of embodiment in many different forms, for the purposes of illustration I have shown only one form thereof in the accompanying drawings, 25 in which—

Figure 1 is a front elevation of an aeroplane made in accordance with my invention;

Figure 2 is a side elevation of the same, 30 partly in section;

Figure 3 is a front elevation of a strengthening plate used in the aeroplane;

Figure 4 is a side elevation of a hollow beam construction located at the rear end 35 of the skid;

Figure 5 is an enlarged vertical section of the fuselage, showing the manner of supporting the skid;

Figure 6 is an elevation of a skid-supporting plate;

Figure 7 is a horizontal sectional view, showing the position of the tail post attached to the fuselage;

Figure 8 is a plan view of the rear end of 45 the fuselage and attached parts;

Figure 9 is a vertical sectional view taken through the edge of one of the openings in the top of the fuselage.

Fig. 10 is a fragmentary sectional view 50 taken on line 10—10 of Fig. 5, looking in the direction of the arrows.

In the drawings, I have shown an aeroplane 1, having a laminated fuselage 2, provided with a motor 3 for driving a pro-

peller 4. The fuselage 2 has two openings 55 5 to receive the operators of the aeroplane. The edges of the fuselage 2 around the openings 5 are protected by upholstery 6^a and a binding strip 6^b to strengthen said edges and protect the same from damage and prevent injury to the operators by coming into contact with said edges. Near the front of the aeroplane in the interior of the fuselage 2, there is a transverse strengthening plate 7 to strengthen the fuselage at this point and 60 to act also as a support for the motor 3. The plate 7 has a peripheral flange 8 for attachment to the interior of the fuselage 2 in any suitable manner. In said plate 7 there are a number of openings 9, where portions of 70 the plate have been cut out to lighten the construction, while retaining adequate strength therein. In the center of the plate 7 there is, furthermore, a central opening 10 to receive the motor 3 and the apparatus 75 associated therewith. At the sides of the opening 10 there are angle plates 11 and 12 to receive longitudinal beams 13, which support the motor 3 at the sides thereof, said beams 13 being supported at the front by 80 brackets 14 attached to the rear side of a plate 14^a, a radiator 15 located at the extreme front foot of the fuselage.

At intervals along the fuselage 2, and in the interior thereof, there are provided 85 strengthening ribs 16, which extend entirely around the interior of the fuselage. At the extreme rear of the fuselage 2, said fuselage is flattened in a vertical plane and provided at the extreme end thereof with a block 17, 90 having steps 18 at the two sides thereof to receive the laminations of the fuselage 2, to which the block 17 is attached in any suitable manner. At the rear end of the block 17 there is a cylindrical recess 19 to 95 receive a tubular tail post 20, which is secured to the block 17 by means of bolts 21. Said tail post 20 extends above the top of the fuselage 2 and into the interior of a triangular vertical fin 23, and near the two 100 ends of the tail post 20 there are provided hinges 24 and 25, carrying a rudder 26. The rudder 26 has two laterally-directed arms 27, to which are attached cables 28, leading into the interior of the fuselage, so that by the movement of the same the position of the rudder 26 may be changed. At the two sides of the rear end of the 105

fuselage 2 there are provided a pair of stabilizer planes 29 and 30, to the rear edges of which are attached hinges 31 and 32 to pivotally support elevators 33 and 34. 5 These elevators are provided, respectively, with pairs of arms 35 and 36, to which are attached cables 37, extending into the interior of the fuselage 2, in order to enable the operator to change the position of the 10 elevators 33 and 34 at will.

Near the rear end of the fuselage 2, there is, furthermore, provided a skid 38, which extends into the fuselage through an opening 39. At one side of the opening 39 and 15 on the interior of the fuselage, there is a transverse plate 40, having a flange 41^a for attachment to the interior of the fuselage 2 in any suitable manner. Said plate 40 is roughly in V-shaped form, so as to receive 20 the skid 38 in the center thereof. Near its lower portion, said plate 40 has an eye-bolt 41, passing through the same, and pivoted to the eye-bolt there is a clamping band 42, which extends around the skid 38. Attached 25 to the upper central portion of the plate 40 there are, furthermore, provided two tubular supports 43 and 44, which are connected at their upper ends to a block 45, having two pairs of wings 46, provided with bolts 47 30 passing through the same. One of said bolts 47 is connected by a cable 48 and a rod 49, having an adjustable link 50, to the tail post 17. The other bolt 47 is connected by a plurality of rubber exerciser cords 51 to a 35 clamping band 52, which surrounds the upper end of the skid 38. Attached to said clamping band 52 there are also laterally-directed rubber exerciser cords 53, the extreme ends of which are connected to rings 40 54, carried by hooks 55, located on plates 56 in a hollow beam 57, extending across the fuselage and filled in with a pair of abutting 45 wooden beams 58 to strengthen the stabilizers 29 and 30. The plates 56 are bolted to the fuselage. There are also provided similar plates 59 at the upper sides of the hollow beam 57, which are similarly bolted to the fuselage. At the two sides of the hollow beam 57, there are strengthening strips 60, 50 which extend around the interior of the fuselage.

The aeroplane operates in the usual manner. However, the transverse strengthening plate 7 adequately strengthens the fuselage 55 2 in a transverse direction, also in a longitudinal direction, as it tends to prevent the collapse of the fuselage, due to bending forces created by conditions in flight or by shock of landing. Strengthening strips 16 60 around the interior of the fuselage have the effect, furthermore, of strengthening the fuselage transversely, as well as longitudinally. Furthermore, by protecting the edges of the fuselage at the openings 5, the 65 portions of the fuselage at this point are

strengthened, while at the same time the operators of the aeroplane are protected from injury by the edges of the fuselage.

In order to change the direction of the aeroplane laterally, the rudder 26 is moved 70 to the right or to the left, as desired, by means of the cables 28. When it is desired to rise or to descend, the elevators 33 and 34 will be operated by means of the cables 37, so as to bring about this result. The 75 entire construction at the rear end of the fuselage is very much strengthened by the presence of the tail post 20 and the block 17, in which it is carried, while at the same time the proper supports are provided for the 80 rudder and adjacent parts. By locating the skid 38 in the manner above described, so that its forward end extends into the interior of the fuselage 2, and is supported in the manner indicated, the skid 38 and the 85 parts attaching the skid 38 to the aeroplane create a minimum of resistance to motion through the air, while at the same time said skid 38 affords an effective means for absorbing shocks when the aeroplane is landing, by reason of the presence of the yielding cords 51 and 53. The cords 53 have the effect, also, of retaining the skid 38 in central position. 90

While I have described my invention 95 above in detail, I wish it to be understood that many changes may be made therein without departing from the spirit thereof.

I claim:

1. An aeroplane fuselage having a pivotally mounted skid extending from the interior to the exterior thereof and a yielding, supporting means for the skid comprising a stretchable binding member at the top of the skid and other similar members at the 105 sides thereof, said binding members being located within the fuselage.

2. An aeroplane fuselage having a pivotally mounted skid extending from the interior to the exterior thereof and a yielding, 110 supporting means for the skid comprising a stretchable binding member and transverse plates in the fuselage located at the pivot of the skid and near the end thereof respectively.

3. An aeroplane fuselage having a pivotally mounted skid extending from the interior to the exterior thereof, a yielding, supporting means for the skid comprising a stretchable binding member at the top of the 120 skid and other similar members at the sides thereof, and transverse plates in the fuselage located at the pivot of the skid and near the end thereof respectively.

4. An aeroplane fuselage having a transverse strengthening plate disposed in the fuselage, a skid extending from the interior to the exterior of the fuselage, means pivotally connecting said skid to said plate, a resilient binding member connected to the in- 125 130

ner portion of said skid, and a support for said binding member extending from said strengthening plate.

5. An aeroplane fuselage having a transverse strengthening plate disposed in the fuselage, a skid extending from the interior to the exterior of the fuselage, means pivotally connecting said skid to said plate, and resilient binding members extending both longitudinally and laterally from the inner portion of said skid.

6. An aeroplane fuselage having a trans-

verse plate disposed therein, said plate having an outer edge portion conforming substantially to the curvature of the fuselage 15 and having its central portion cut away, a skid extending from the interior to the exterior of the fuselage and supported intermediate its length from said plate, and binding members extending between the fuselage 20 and the upper end of said skid.

In testimony that I claim the foregoing I have hereunto set my hand.

CHARLES F. WILLARD.
